DESIGN FOR A SIGNAL LIGHT

Jeremiah D. Kennelly, Oak Park, Ill., assignor of
one-half to Ethel V. Mars

Application November 11, 1936, Serial No. 65,859

Term of patent 7 years

To all whom it may concern:

Be it known that I, Jeremiah D. Kennelly, a citizen of the United States, residing at Oak Park, county of Cook, and State of Illinois, have invented a new, original, and ornamental Design for a Signal Light, of which the following is a specification, reference being had to the accompanying drawing, forming a part thereof, in which:

Figure 1 is a front elevational view of a signal light showing my new design; Fig. 2, a side elevational view; and Fig. 3, a plan view.

I claim:

The ornamental design for a signal light, as shown.

JEREMIAH D. KENNELLY.
